(57) **CLAIM**

The ornamental design for a busbar-less solar cell, as shown and described.

DESCRIPTION

FIG. 1 is a top perspective view of the first embodiment of a busbar-less solar cell showing our new design;

FIG. 2 is a bottom plan view thereof;

FIG. 3 is a top plan view thereof;

FIG. 4 is an alternative bottom view of the busbar-less solar cell, according to the embodiment of FIG. 1 of the design

FIG. 5 is a right side elevation view thereof;

FIG. 6 is a left side elevation view thereof;

FIG. 7 is a back side elevation view thereof;

FIG. 8 is a top perspective view of the second embodiment of a busbar-less solar cell showing our new design;

FIG. 9 is a bottom view thereof;

FIG. 10 is a top plan view thereof;

FIG. 11 is a right side elevation view thereof;

FIG. 12 is a left side elevation view thereof;

FIG. 13 is a back side elevation view thereof; and,

FIG. 14 is a front elevation view thereof.

The broken lines shown are included for the purpose of illustrating a portion of the busbar-less solar cell that form no part of the claimed design.

Applicant reserves the right to amend the claimed invention by showing in solid lines any and all features or portions thereof originally shown in broken lines and/or by showing in broken lines any and all features or portions thereof originally shown in solid lines.
